UNITED STATES PATENT OFFICE.

CLARENCE S. MOORE, OF LEXINGTON, KENTUCKY.

VALVE.

Application filed September 28, 1925. Serial No. 59,197.

This invention relates to valves and more particularly to a valve adapted for use in connection with a pressure chamber having a member therein adapted to be operated by differential pressure controlled by the valve.

In my prior Patent No. 1,522,692, I have shown and described an attachment for motor vehicles comprising a cylinder, a piston mounted therein and adapted to be moved in one direction by differential pressure and to be returned to normal position by a spring, and a plurality of pivoted leaves adapted to be actuated by said piston to form a glare shield for use in connection with motor vehicles. In the present case I have illustrated a similar device wherein a source of pressure or vacuum is adapted to be connected to either end of the cylinder to operate the piston, the spring means being omitted. The subject matter of the present invention comprises a novel form of valve adapted to control communication between the opposite ends of the cylinder and a source of such vacuum as the intake manifold of an automobile engine.

An important object of the invention is to provide a simple form of valve structure having novel means for affording communication between one end of the cylinder of the glare shield and the atmosphere.

A still further object is to provide a valve of the above mentioned character wherein each of the ports provided in the valve may be drilled therein thus simplifying the construction and making it cheaper to manufacture.

Other objects and advantages of the invention will become apparent during the course of the following description.

In the drawings I have shown one embodiment of the invention. In this showing:

Figure 1 is a face view of the glare shield in position,

Figure 2 is a central vertical sectional view through the glare shield, parts being shown in elevation,

Figure 3 is a side view of a portion of a motor vehicle showing the device applied,

Figure 4 is a detail view of the leaves of the glare shield,

Figure 5 is a central sectional view through the valve taken at right angles to the axis thereof,

Figure 6 is a detail sectional view on line 6-6 of Figure 5, and,

Figure 7 is a similar view on line 7-7 of Figure 6.

Referring to the drawings, the numeral 10 designates a motor vehicle having an engine 60 11 provided with the usual intake manifold 12. The vehicle is provided with a windshield 13 mounted in the usual frame 14.

A supporting member 15 is secured to the windshield and is provided with a substantially U-shaped depending portion 16 adapted to receive a plurality of leaves 17 pivotally connected to the support as at 18. One of the leaves 19 is provided with a pin 20 secured thereto and extending transversely 70 from the inner face thereof. Each of the other leaves is provided with an arcuate extension 21 having a slot 22 therein to receive the pin 20. Each of the slots 22 is progressively longer in each of the extensions 21 75 from the leaf 19 to the farthest leaf 23. Thus it will be apparent that the lifting of the leaf 19 from the position shown in Figure 2 to the positions indicated in Figures 1 and 4 will cause the other leaves to be successively raised, thus providing in effect a solid sheet to act as a glare shield. The leaf 19 is provided on the opposite side of the pivot 18 with an extension 24 having a slot 25 therein. The extension 24 extends 85 through a slot 26 formed in a cylinder 27. A piston 28 is mounted to reciprocate in the cylinder 27 and is provided with a transverse pin 29 adapted to engage within the slot 25 to move the leaf 19 upwardly when 90 the piston 28 travels downwardly in the cylinder. Pipes 30 and 31 communicate with either end of the cylinder 27, as shown in Figure 2.

Referring to Figures 5, 6 and 7, the numeral 32 designates a substantially cylindrical valve body having a tapered opening 33 to receive a similarly shaped valve 34. The valve is provided with a radial opening 35 extending entirely therethrough and this 100 opening communicates with a second radial opening 36 drilled half way through the valve and at right angles to the opening 35. The valve is provided opposite the opening 36 with an angular port 37 the upper end 105 of which is arranged substantially in the same plane as the openings 35 and 36. The valve body is provided with opposite aligned openings 38 and 39, and is further provided with a radial opening 40 arranged between 110 110 and in the same plane as the openings 38 and 39. The openings in the valve body just de-

scribed are obviously arranged in the same plane as the openings 35 and 36 and the upper end of the port 37 to communicate therewith under certain conditions to be described.

The valve body is provided at its upper end with shoulders 41 adapted to contact with pins 42 carried by the valve to limit rotating movement of the latter. The valve is provided at its upper end with an enlarged head 43 having an operating handle 44 connected therewith.

The lower end of the valve 34 is arranged substantially flush with the lower end of the valve casing and a washer 45 is arranged thereagainst. The lower end of the valve is internally threaded to receive the threaded end of a plug 46 having an enlarged head 47 adapted to contact with the lower face of the washer 45. The plug 46 is provided with an axial opening 48 communicating with the lower end of the port 37. Each of the openings and ports previously described in connection with the valve, casing and plug is formed by drilling whereby the structure may be cheaply manufactured. In the drilling operation, the openings 35, 38 and 39 may be drilled in a single operation after which the valve may be rotated one quarter of a turn to permit drilling of the opening 36 through the opening 39. The port 37 may be drilled through the side of the valve before the latter is placed in position.

The pipe 31 is connected to the valve casing by a suitable union 49 whereby it communicates with the opening 38, while the pipe 30 may be similarly connected to the valve casing by a union 50 to afford communication with the opening 40. A third pipe 51 is connected to the valve casing by a union 52 whereby it communicates with the opening 39, the opposite end of the pipe 51 being connected with the intake manifold 12 to communicate therewith as shown in Figure 3. The valve body may be mounted in any convenient place accessible to the driver of the vehicle and in the present instance I have illustrated a bracket 53 connecting the device to the steering post of the vehicle.

The operation of the device is as follows:

When approaching a vehicle having glaring headlights which it is desired to shield from the eyes of the driver, the handle 44 may be rotated to place the valve 34 in the position shown in Figure 5 whereupon communication will be afforded between the lower end of the cylinder 27 and the intake manifold through pipes 31 and 51 and openings 35, 38 and 39. The upper end of the cylinder 27 will communicate with the at-

mosphere through pipe 30, opening 40, port 37 and opening 48 to permit air to enter the upper end of the cylinder 27 whereby the piston may freely move downwardly. This action depresses the arm 24, lifting the leaf 19 and the succeeding leaves to provide a glare shield substantially of the character shown in my prior Patent No. 1,522,692 referred to above. As long as the valve remains in the position shown in Figure 5, the shield will be maintained in operative position. When the valve 34 is rotated one quarter turn in a clockwise direction as viewed in Figure 5, communication will be afforded between pipes 30 and 51 through openings 35, 36, 39 and 40 to connect the upper end of the cylinder 27 to the intake manifold. At the same time, the lower end of the cylinder 27 will communicate with the atmosphere through the pipe 31, opening 38, port 37 and opening 48, thus allowing free upward movement of the piston 28. The upper end of the cylinder 27 will be in constant communication with the intake manifold when the leaves of the glare shield are in inoperative position and the suction of the manifold tends to hold the leaves in inoperative position to prevent rattling thereof.

It is to be understood that the form of my invention herewith shown and described is to be taken as a preferred example of the same and that various changes in the shape, size and arrangement of parts may be resorted to without departing from the spirit of the invention or the scope of the subjoined claim:

I claim:

A device of the character described comprising a substantially cylindrical valve body provided in its sides with an inlet opening and a pair of outlet openings arranged in the same plane at right angles to the axis of said valve body, and a rotatable valve arranged in said valve body, said valve being provided with an opening extending diametrically therethrough and an opening extending halfway therethrough at right angles to and communicating with said last named opening, said valve being further provided with an inclined vent port, one end of said port and the openings in said valve being arranged in the same plane as the openings in said valve body, said valve being provided in one end with a threaded axial opening, and a plug threaded in said axial opening and provided with an opening communicating with the other end of said port, said plug being adapted to maintain said valve in said valve body.

In testimony whereof I affix my signature.
CLARENCE S. MOORE.
